ELECTRON DISCHARGE TUBE

Application filed May 14, 1923, Serial No. 638,932, and in the Netherlands October 21, 1922.

This invention relates to electron discharge tubes and more particularly to discharge tubes provided with a sealed envelope which consists at least partly of vitreous material. 5 Still more particularly the invention relates to the attachment of one or more electrodes in the interior of such discharge tubes. The invention is applicable to discharge tubes such as X-ray tubes, rectifiers, tubes provided 10 with three or more electrodes for wireless telegraphy, telephony and similar purposes, having either a high vacuum or a gaseous filling.

The invention is particularly advantageous 15 when applied to transmitting or receiving tubes of high capacity for wireless telegraphy, telephony and similar purposes.

For the attachment of the grid and the anode in tubes with three electrodes, resilient clamps or similar devices have hitherto been used, to which the electrodes were fixed 20 by means of supports.

The object of the present invention is an improvement of the attachment of electrodes 25 and more particularly its object is to provide a simple and rigid construction, where only a small quantity of metal is used for the attachment.

The discharge tube according to the invention, which is provided with a sealed envelope consisting at least partly of vitreous material, is characterized in that within said envelope at least one electrode is supported by at least one bar shaped support fixed to a 35 connecting member, said member being fused to the glass of the tube along a portion of its surface materially larger than the surface of the end of a bar-shaped support. The connecting member consists at least at the place of fusing-in, of a metallic material which readily adheres to the vitreous material of the envelope and which has a coefficient of thermal expansion differing little from that of the vitreous material.

40 As a material for the connecting-member chrome-iron containing 10-50% of chromium is particularly suitable.

The electrode can be connected to the connecting-member (preferably annular) by 45 means of one or more chrome-iron supports.

The invention is particularly advantageous when one or more sealing-members are fused with the wall or the end of a glass tube, which is hermetically closed and is fused with the vitreous or metallic wall of the discharge- 55 tube.

The glass tube can be hermetically closed by a glass stem which is fused with the tube and in which one or more leading-in wires are embedded. The tube may also be hermetically closed by a disc consisting of metallic material that does not generate gases during the fusing operation and has a coefficient of expansion substantially the same as that of the glass. Said disc is fused at its 60 circumference with the glass of the tube and serves for the passage and the attachment of a leading-in wire. ● ●

The device according to the invention is particularly advantageous when the glass 70 tube is hermetically closed by several discs of metallic material that do not generate gases during the fusing operation and have a coefficient of expansion substantially the same as that of the glass. Each of these discs can 75 be used for the attachment of one leading-in wire and the discs are, at least along a portion of their circumference, hermetically connected together by a glass layer. These discs have such a shape that the remaining parts 80 of their circumferences together correspond to the cross-section of the glass tube. Preferably the discs may be shaped as sectors or segments of a circle.

In the accompanying drawings some embodiments of the invention are diagrammatically represented by way of example.

Fig. 1 is a view of a discharge-tube with 85 three electrodes. The plate and the grid are fixed to glass tubes.

Fig. 2 is an end-view on an enlarged scale of the glass tube that supports the grid and the filament according to Fig. 1.

Fig. 3 illustrates another construction of a fixing-device according to the invention. 95 The interior of the glass tube is closed by a glass stem, in which two leading-in wires are embedded.

Fig. 4 is a view of a discharge tube provided with three electrodes, which are sup- 100

ported by one glass stem. By means of supports the anode and the grid are fixed to metal rings which are fused to the ends of two co-axial tubes and in the inner tube two sector-shaped discs carrying the filament are fused.

Fig. 5 is an end-view of the glass stem according to Fig. 4.

Fig. 6 and Fig. 7 show a construction in which the connecting-member is not ring-shaped but comprises an arc-shaped plate.

Fig. 8 is an end-view of a construction similar to that shown in Figs. 6 and 7. The glass tube is closed by three sector-shaped discs.

Fig. 9 shows the fixing of the glow-cathode in an X-ray tube, and

Fig. 10 shows a construction in which the sealing-member comprises a flat ring the circumference of which is fused with the wall of a glass tube contained in the bulb.

In the discharge tube with three electrodes shown in Fig. 1 the invention is applied to the attachment of the anode and the grid. The construction shown in the said figure is particularly advantageous for generating tubes of high capacity, for example more than 1 kilowatt, for wireless telegraphy, telephony and similar purposes.

The tube has a glass wall 1 with which the glass tubes 2 and 3 are hermetically fused. To the end of the glass tube 2 a metal ring 6 is fused, to which the anode 4 is fixed by means of supports 5. The interior of the tube 2 is hermetically sealed by a glass stem 7, in which a leading-in wire 8 for the anode is embedded. In a similar manner a metal ring 9 is fused to the end of the glass tube 3 and the grid 11 is fixed to said ring by means of bar-shaped supports 10. A leading-in wire 12 for the grid is fused at 13 in the wall of the tube.

As a material for the rings 6 and 9 any metal or metal alloy is suitable which readily adheres to glass and has a thermal coefficient of expansion substantially the same as that of the glass, as otherwise cracks would occur in the glass when fusing the rings to the end of the glass tubes. It will however be apparent from the nature of the construction that the seal between the glass and the metal need not be hermetic.

It has been found that chrome-iron of a certain composition is particularly suitable as a material for the rings. The composition of the chrome-iron depends on the nature of the glass used.

The difference between the coefficient of expansion of the material of the ring and that of the glass can be greater than is allowable with leading-in wires. Differences up to 20% have no deleterious effect when fusing in.

Good results are obtained when the alloy contains 10-50% of chromium. In a particular case, when fusing on to X-ray glass or to

the so-called "potassium sodium glass" an alloy containing about 17-20% of chromium has given satisfactory results.

Small quantities of impurities may occur in the chrome-iron without decreasing the suitability of the material. These impurities can have some influence on the coefficient of expansion, owing to which the composition must be somewhat varied.

The impurities may have been introduced into the alloy because they were already present in the elementary body such for example as carbon in iron, but it may also be necessary that, when melting together the two metals chromium and iron, small quantities of certain admixtures, such for example as manganese or silicon, should be used. It is desirable however that the percentage of the impurities should always be small.

The thickness of the metal ring should not be too small in connection with the attachment of the electrodes although the edge embedded in the glass should be thin. It has been found however that even chrome-iron rings having at the edges a thickness of 1 to 2 millimeters are very readily sealed to glass, which removes any difficulty experienced in this respect.

Also metals or alloys other than chrome-iron are suitable for the purpose of the invention. When using for instance the so-called "Pyrex glass" which is frequently used in America, also molybdenum or tungsten are suitable. In the case of lead-glass or X-ray glass, nickel-iron which is freed from all occluded gases can be used whilst good results can also be obtained with the so-called compounded rings having for example a nickel-iron core and a thin platinum layer. Platinum is less suitable for the purpose of the invention as, in the first place, it is too expensive and moreover platinum rings having a relatively large thickness, $\frac{1}{2}$ to 1 mm. for example, are very difficult to fuse in.

The use of chrome-iron is also advantageous because, as a rule, this material absorbs but a very little quantity of gas and consequently it generates but a small quantity of gas when introduced into the tube. In connection with the purpose of obtaining a high vacuum in the tube this is a considerable advantage.

It is also possible to free the chrome-iron from occluded gases by melting it in a vacuum, for example, prior to its introduction into the tube, although it is not necessary to do so.

The device for fixing the electrodes according to the invention is particularly advantageous when combined with a process of leading the current through, such as has been applied to the glass tube 3. The interior of the latter is sealed by two semi-circular discs 18 and 19 to which leading-in wires 20 and 21 for the filament 15, 16 are fixed on both sides.

As a material for the discs such metals or alloys are generally suitable which do not generate gases during the fusing operation, which readily adhere to glass and which have 5 a coefficient of expansion substantially the same as that of the glass. As a rule the same materials may be used as mentioned before for the rings 6 and 9 but the conditions to be observed with regard to the discs are more 10 severe because a perfectly hermetic seal must be obtained. Again the use of chrome-iron of suitable composition offers great advantages.

Regarding the properties of the chrome- 15 iron the same remarks may be made as those hereinbefore mentioned.

The process of leading the current through such as has been applied to the glass tube 3, is in general characterized by the sealing in of 20 several discs which, along a portion of their periphery are hermetically connected together by a glass layer whilst the remaining parts of their peripheries together correspond to the cross-section of the glass tube. 25 Generally the periphery of the discs connected together should be a circle.

The discs may be shaped into any form desired. Preferably, care should be taken that the discs can be sealed together by a relatively 30 thin glass layer, after which the free part of the periphery of at least one of the discs may be fused in the glass tube. One or more discs may, along the whole of their periphery, also be connected to the other disc or discs. 35 For example a circular and an annular disc may be connected by an intermediate glass ring, and then the annular disc with the glass tube may be melted together. Preferably, however, the disc consists of segments or sec- 40 tors of a circle. Although not necessary the most simple course is to use flat discs and to connect them by the surrounding glass to form one larger flat disc.

It is advisable that the discs, before being 45 fused in the glass tube, should be surrounded by a thin glass layer.

The leading-in wires may be fixed to the discs in various ways. They may be led through holes in the discs and fixed thereto by 50 soldering, welding or in any other way. In so doing, however, there is a risk of forming air-leaks in the seal and therefore the leading-in wires should be preferably fixed to the discs on both sides, as shown in Fig. 1, by 55 soldering or welding for example. When chrome-iron discs are used it is desirable that the parts of the leading-in wires that are fixed to the discs should be made of nickel, as the latter metal is readily and easily fixed to 60 chrome-iron by welding.

The use of chrome-iron as a material for the discs is also advantageous because the said material is practically non porous and permits obtaining a permanent high vacuum 65 within the tube.

The end of the glass tube 3 of Fig. 1 is illustrated on a larger scale in Fig. 2.

Another embodiment of the invention is shown in Fig. 3. A glass tube 25 is fused with the wall of a discharge tube which is not 70 shown. Said wall may be of glass or of metal. To the end of the tube 25 a ring 26 is fused in, to which the electrode is connected by means of supports 27. At the other end the tube 25 is hermetically sealed to a disc 30 by 75 a stem 29, which is placed in the reverse manner to that commonly adopted. Such an arrangement of the stem offers the advantage that the pinch 31 in which the leading-in 80 wires 32 and 33 are embedded is more distant from the filament 34, so that the pinch is prevented from reaching too high a temperature.

In Fig. 4 a discharge tube is shown provided with three electrodes which are all supported on the same side of the tube by a glass 85 stem. A glass tube 36 is fused with the glass wall 35 of the discharge tube. The filament 44 is supported by its leading-in wires which are fixed to sector-shaped discs 45 and 46 which hermetically seal the interior of the 90 glass tube 36. The grid 38 is connected by supports 39 to a metal ring 37, which is fused to the end of the tube 36. A second tube 43, to the end of which a ring 42 is fused, is also fused with the said tube 36. The latter ring 95 supports the plate 40 by means of bar-shaped supports 41. Leading-in wires 47 and 48 for plate and grid are fused into the glass-wall of the tube in the known manner. The way of suspending the filament, the construction 100 of the electrodes and their arrangement with relation to each other are also known.

Fig. 5 is an end-view of the glass stem of the tube illustrated in Fig. 4.

Fig. 6 represents diagrammatically an embodiment of the invention provided with an arc-shaped connecting-member instead of an annular one for fixing the electrodes. To the end of the tube 50 two arc-shaped connecting-members 51 and 52 are fused, having attached thereto supports 54 and 53 for fixing the electrodes. The latter operation may be effected in any suitable way for example by soldering or welding.

As a material for the supports nickel is 115 suitable for all constructions according to the invention.

The use of chrome-iron for the supports is particularly advantageous as the small heat-conductivity of said material prevents an undesired heat-conduction to the glass.

The interior of the tube 50 is hermetically sealed by the stem 55, in which the leading-in wires 56 and 57 are embedded.

Fig. 8 is an end-view of a fixing-device 125 provided with connecting-members 61 and 62 of the same shape as those shown in Fig. 7. The glass tube is however hermetically sealed by three sector-shaped discs 58, 59 and 60, which may serve for example for fixing the 130

leading-in wires for the filament and those for the grid and for leading them through.

In Fig. 9 an application is shown of the invention to X-ray tubes in which the device according to the invention is used for fixing the glow-cathode. A glass tube 66 to the end of which the ring 67 is fused, is fused with the wall 65 of the tube. To said ring the supports 68 are fixed, to the end of which is attached a collecting-device 69. One end of the coiled filament 73 is fixed to the collecting-device and the other end (the centre of the coil) is fixed to a leading-in wire 72 which is embedded in the stem 70. The other leading-in wire 71 is fixed to one of the supports 68.

In the construction shown in Fig. 10 the sealing-member comprises a flat ring of chrome-iron or any other suitable metallic material. The internal circumference of said ring is fused with the wall of a glass tube 80, which is hermetically fused with the wall of the discharge tube. The glass tube is hermetically sealed at 81 and a leading-in wire 82 is hermetically fused into the seal. The electrode 85 is connected to the sealing-member 83 by metal supports 84 as in the other constructions. It is clear that also at other points the sealing-member may be fused with the wall of the discharge tube.

It will be apparent to persons skilled in the art that where in the accompanying drawings discharge tubes are shown, with a sealed envelope entirely consisting of vitreous material, the present invention may also be applied to tubes the envelopes of which partly consist of metal; for example it may be applied to discharge tubes the anode of which forms part of the wall of the tube.

What we claim is:

1. An electrical discharge device comprising a sealed envelope having a re-entrant tubular stem of vitreous material, an electrode mounted in said envelope, a support for said electrode comprising bars secured at their upper ends to said electrode and having at their other ends a connecting member of a metal having substantially the same co-efficient of thermal expansion as said vitreous material, said connecting member having a thin curved edge conforming in shape to and embedded in the outside of the curved wall of said tubular vitreous stem by fusion of said vitreous material in juncture with said connecting member, a cooperating electrode mounted in said envelope, and leading-in wires for said electrodes hermetically sealed into the walls of said envelope and connected to said electrodes.

2. An electrical discharge device comprising a sealed envelope having a re-entrant glass stem with a tubular inner end, an electrode mounted in said envelope, a support for said electrode comprising bars secured at their upper ends to said electrode and having

on their other ends a connecting member of a metal having substantially the same co-efficient of thermal expansion as said glass and curved to conform to the shape of the inner end of said stem, one edge of said connecting member being embedded in the end of said tubular stem by fusion of said glass in juncture with said edge of said connecting member, a cooperating electrode mounted in said envelope, and leading-in wires for said electrodes hermetically sealed into the walls of said envelope and connected to said electrodes.

3. An electrical discharge device comprising a sealed envelope having a re-entrant glass stem with a tubular inner end, an electrode mounted in said envelope, a support for said electrode comprising bars secured at their upper ends to said electrode, and having at their other ends a ring member of a metal having substantially the same coefficient of thermal expansion as said glass and having a thin edge curved to conform to the shape of the inner end of said stem and embedded in the outside of the curved wall of said tubular stem near the inner end thereof by fusion of said glass in juncture with said thin curved edge of said member, a cooperating electrode mounted in said envelope, and leading-in wires for said electrodes hermetically sealed into the walls of said envelope and connected to said electrodes.

4. An electrical discharge device comprising a sealed envelope having a re-entrant glass stem with a tubular inner end, an electrode mounted in said envelope, a support for said electrode comprising bars secured at their upper ends to said electrode and having at their other ends a connecting ring of metal having substantially the same co-efficient of thermal expansion as said glass and of substantially the size and shape of the tubular inner end of said stem, and having a thin curved edge embedded in the end of said tubular stem by fusion of said glass in juncture with said thin edge of said ring, a cooperating electrode mounted in said envelope, and leading-in wires for said electrodes hermetically sealed into the walls of said envelope and connected to said electrodes.

5. An electrical discharge device comprising a sealed envelope having a re-entrant tubular glass stem, an anode mounted in said envelope, a support for said anode comprising bars secured at their upper ends to said anode and having at their other ends a connecting ring member of a chrome iron alloy having substantially the same co-efficient of thermal expansion as said glass, said ring member having a thin curved edge conforming in shape to and embedded in the outside of the wall of said tubular stem by fusion of said glass in juncture with said curved edge of said plate, two semi-circular discs consisting of said chrome iron alloy

hermetically connected together along their straight abutting edges by a layer of glass to form an imperforate circular disc hermetically sealed at its periphery to the inside
5 walls of said stem to hermetically close it, a conductor fixed to the inner surface of each of said semi-circular discs to project along the bore of said stem toward the interior of said envelope, a filamentary cathode connected to said conductors, a leading-in wire hermetically sealed into the wall of said envelope and connected to said anode, and a current supply lead, connected to the exterior surface of each of said semi-circular discs.
